STORM SASH CONSTRUCTION

Filed May 4, 1922

2 Sheets-Sheet 2

UNITED STATES PATENT OFFICE.

JAMES H. GIBSON, OF BROOKLYN, NEW YORK.

STORM-SASH CONSTRUCTION.

Application filed May 4, 1922. Serial No. 558,372.

To all whom it may concern:

Be it known that I, JAMES H. GIBSON, a citizen of the United States, and a resident of Brooklyn, in the county of Kings and State of New York, have invented certain new and useful Improvements in Storm-Sash Constructions, of which the following is a specification.

My invention relates to building closures. 10 The object of my invention is to provide a frame and sash construction which may be used in conjunction with the usual sash and window construction commonly used in building residences and in this connection 15 serves to make a more complete shelter for the room which it protects in winter time.

A further object is to provide a sash construction adapted to hold removable sash units which may hold glass sheets such as 20 used in buildings, or screens of wire mesh, or cloth, or metal sheets, or boards, etc., which are interchangeable and may be removed or changed at will and in an easy way.

25 A further object is to provide a frame and sash construction which may be manufactured and sold as an independent article of manufacture so that any one having a residence may purchase and install the sash in 30 the building without employing a skilled mechanic.

The novel features of construction are herein set forth and claimed, it being understood that the main casing or frame is 35 adapted to hold any of the sash units made as a part of the construction, all of which are preferably made of the same size and shape as to their frame dimensions, and will therefore fit any space provided in the main 40 frame or casing.

Referring to the drawings which form a part of this application,

Figure 1 is a perspective view of a frame and sash construction as it appears when 45 installed in a window casing of a residential building, one side of said casing being shown in vertical section to disclose the means used in holding the frame securely in position in said casing.

50 Figure 2 is a view shown in vertical cross-section taken on line 2-2 of Fig. 1.

Figure 3 is a horizontal view taken on line 3-3 of Figure 1.

55 Figure 4 is a side view of the frame shown partly in section, and means carried thereby

to support a sash in inclined relation therewith.

Figure 5 is an illustrational view showing some details of the sash construction and means used for holding the sash in position 60 in the frame.

Figure 6 is a view illustrating the thumb-nut construction employed to hold the sash in the frame.

Figure 7 is a view of the inner side of the 65 frame with the board construction used when the house is closed for a season or at night for purposes of safety or during a violent storm, etc.

Figure 8 is a perspective view of the outer 70 side of said board construction.

Figure 9 is a view of a window mounted in the frame and viewed from the inner side of the room.

Figure 10 is a perspective view of a sash 75 unit.

A, indicates the window casing of a building of the usual type constructed for a residence.

B and B' respectively indicate the usual 80 guide channels for the sashes generally used, which are not herein shown.

C—indicates my new frame which is set in the casing A on the outer side thereof at 85 a short distance, usually from one to four inches from the channel B', and held therein by laterally extending screws C'—C' etc. which extend through the frame C and into the casing A.

D indicates one of the removable sash 90 units which is preferably made rectangular in form and fits closely within a rectangular shaped recess D' formed in the frame C, and against a cloth or felt packing abutment

strip D² cemented or otherwise fastened permanently to the frame C. Each sash is provided with four corner angle braces of metal E—E, etc., to hold the frame together and at the same time to provide a wearing surface for the face of the thumb-nuts F and 95 spring-clips G which bear against it.

As shown in Figure 6, the thumb-nut F is carried by a threaded bolt F' which extends through the frame C from the outer side thereof, the nut screwing on the bolt 100 F' and bearing against the metal plate E mounted in the frame D. The face of the nut may be oblong in shape so that when turned in locked relation to the sash D it

105 overlaps the sash to hold it in the frame C 110

and when turned a quarter turn it unlocks the sash. A yielding cushion H preferably of soft rubber, is interposed between the face of the frame C and nut F and serves 5 to prevent the nut from unscrewing and to hold the bolt F' from rattling when the nut is in unlocked relation with the frame D. The end of the bolt is upset after the nut is 10 screwed thereon to prevent the bolt from being unscrewed from the outside by any one.

The frame C is provided with a cross strip C² through which extend two of pins I—I respectively which serve as a support for 15 the upper sash D and also serve to hold a metal strip J which extends across the frame C and is attached thereto at each end by screws J'—J' respectively. These pins also serve to hold the two spring clips G—G 20 in operative position.

One or more pins indicated by K may also be used as illustrated to support the strip J and also the upper sash D. Where 25 the frames are very large, two sashes may be used as indicated in Figure 1.

Referring to Figures 4 and 5, in order to 30 secure ventilation of the room, provision has been made to support the sashes having air tight panels therein such as glass, in open and inclined relation to the frame C as illustrated. The frame C is provided with a shallow recess L—L respectively in each side thereof near its upper end, and a metal support M is held in each recess by a screw 35 M' on which it swings. The support M is provided with a slot M² with one or more lateral extensions M². A pin N is carried by each side of the respective sash D and extends into the adjacent slot M² and may rest 40 in either of the extensions thereof to hold the sash at the desired angle. These supports M are made of spring material and readily bend in a lateral direction to permit the removal of the sash when it is desired to 45 remove the same from the frame C.

Recesses O—O are provided in the frame C to receive the projecting pins N—N respectively when the upper sash D is placed 50 in the lower portion of frame C.

Figures 7 and 8 show the construction of 55 the board panel indicated by P, the two vertical strips P'—P' respectively being placed on the exposed side of the said panel D.

The lower end of the upper sash and the 60 upper end of the lower sash rest under the overlapping portions of the metal band J which holds them in position and therefore it is only necessary to unlock the thumb-nuts F in order to freely remove the sashes.

Now it will be noted that when each of

the sashes contains glass panes, and the regular sashes which are supported in the channels B and B' are closed, a closed space or chamber is formed between them the size of which depends upon the distance they are 65 spaced apart from each other, and therefore in winter time an air seal or insulating chamber is provided which serves materially in preventing the heat within the room from being conducted away. 70

It will be observed that the sashes are placed in and removed from their supporting frame entirely from the inside of the room, thus making it easy to remove them for purposes of cleaning, etc., and also preventing the window from being opened from the outside, and all locking and fastening means are also located on the inner side, protecting them in bad weather and if deemed desirable, the inner windows could be dispensed with and this type of construction 80 substituted. 75

Having thus described my invention I claim as new:

1. In a closure construction comprising a 85 frame, an upper and lower panel member therein and retaining means carried by the upper and lower rails of said frame and engageable with the adjacent edges of said members, the combination of a strip having shoulders and extending transversely across said frame, a band cooperating with said shoulders to form a recess receiving the lower edge of said upper member and the upper edge of the lower member respectively, 90 spring clips engaging the respective sides of said members, and fastening means passing through said clips and said band and securing them to said strip. 95

2. In a closure construction comprising a 100 frame, an upper and lower panel member therein and retaining means carried by the upper and lower rails of said frame and engageable with the adjacent edges of said members, the combination of an abutment 105 piece having shouldered recess thereon including a band-plate and mounted in position to receive the lower edge of the upper member and the upper edge of the lower member respectively, spring clips engaging 110 the respective sides of said members and fastening means passing through said clips and band-plate and securing them to said abutment piece. 115

Signed at New York, in the county of New York and State of New York, this 17th day of April A. D. 1922.

JAMES H. GIBSON.
Witness:
FRANK M. ASHLEY.
